UNITED STATES PATENT OFFICE.

CHARLES W. HAMEL AND LOUIS J. HAMEL, OF ST. LOUIS, MISSOURI.

PROTECTOR FOR GOLF CLUBS.

Application filed February 17, 1926. Serial No. 88,853.

Our invention relates generally to golf clubs and more particularly to protectors for same.

Each golf club is provided with a grip which is usually formed by winding a strip of leather or similar material on the enlarged end of the club to provide a more firm grip. The end of the leather strip is generally tacked to the stick and is usually protected by a layer of twine, which is wound on the stick and extends a considerable distance beyond the end of the leather covering. A similar coil of twine is used to protect the socket portion of the head and reinforce the same where the end of the shaft joins the head of the club.

In replacing the club in the bag in which it is usually carried, this winding of twine strikes the edge of the bag and is subjected to constant wear and tear, so that in a short period of time the twine is broken or loosened, exposing the end of the leather cover, which in turn is subjected to constant rubbing against the edge of the bag, tearing the same or loosening it from the club.

It is the object of the present invention to provide a protector in the form of a resilient member which can be readily placed on the club over the end of the leather covering and over the socket portion of the head thereby protecting the edges thereof and reinforcing the same.

Other objects of our invention are to form a tubular member adapted to be placed over the annular edge of the leather covering and secured into position thereon, said tubular member having tapering ends so as to eliminate projecting edges striking against the edge of the bag.

Additional objects of our invention are to provide an auxiliary covering for the end of the shaft which covering is simple and inexpensive to make and can be readily replaced when worn out or broken.

With these and other objects in view our invention consists in certain novel features hereinafter more fully described as shown in the accompanying drawings, in which:—

Figure 1 is a perspective view of a golf club equipped with our protectors.

Figure 2 is a longitudinal cross section through a portion of the handle of the club.

Figure 3 is a vertical cross section taken on line 3—3 of Figure 2.

Figure 4 is a longitudinal cross section showing a modified form of a protector.

Figure 5 is a longitudinal cross section through another modified form of the protector.

Figure 6 shows another modified form of the protector.

Figure 7 shows a tool designed to be used in placing a protector over the handle of the club.

Referring by numerals to the accompanying drawings which represent a golf club comprising a shaft 11, the lower end of which is seated in a socket formed in shank 12 of a head 13. The opposite end of shaft 10 is enlarged and tapers towards shaft 11 to form a handle 14 which is provided with a strip of leather or rubber covering 15 which forms a suitable covering for aforesaid handle. This covering extends a suitable distance from the end of the club, and the end of the leather strip is usually covered by a twine 16 tightly wound on the shaft and on said leather strip 15 as shown in Figure 2. A protector 17 of tubular shape and having tapering ends 18 is placed over the twine covering and is of sufficient length to enclose a suitable portion of shaft 11 and the leather covering 15. This protector may be secured in position in any suitable manner and protects the terminal edges of said leather covering. The tapered ends 18 minimize the edge contact with the bag when the club is removed from or replaced in the bag.

A protector 19 of similar shape is placed over the shank 12 and the lower portion of shaft 11. Protectors 18 and 19 not only serve to protect the edges of covering 15 and shank 12, respectively, against injury, but also reinforce the club at these points. In the form shown in Figures 2 and 3 the protector is placed on shaft 11 over the lower end thereof, the latter is then secured in the socket of shank 12. The protector is preferably formed of resilient material such as rubber so that when the

protector is moved in position it will be held therein by its own tension. In the form shown in Figure 4 protector 20 is formed of resilient material and is provided with an internal screw thread 21 which facilitates the positioning of the protector on the club. In the form shown in Figure 5 the protector 22 is formed of a strip of metal 23, coiled in tubular form and is resilient so that said protector may be expanded to increase the diameter thereof when placing the same in position. In Figure 6 is shown a pro-

tector 24 which is formed by winding a strip of rubber in position on the club and then vulcanizing said strip so as to permanently secure the protector in position.

6 In all of the cases the ends or angular edges of the protectors are tapered so that the peripheral surfaces of the protectors merge with the surface of the club, thereby eliminating all projecting abrupt surfaces.

10 Each protector can be distinctively marked or colored so as to distinguish the particular club from other clubs or to indicate ownership of such club and also to enable the player to better observe the angle of the 15 backward and forward swing of the club in the course of practice.

Where the protector is to be placed in position over the handle or enlarged end 14, suitable means or tool, such as 25 shown in 20 Figure 7 may be used to expand the tubular member.

This tool comprises handles 26 and jaws 27 the latter being preferably disposed at right angles to handles 26 and tubular in 25 cross section tapering to one end. The pro-

tector is slipped over the jaws, which are then expanded to enlarge the internal diameter of said protector in order to permit the latter to be slipped over the handle. When the protector is passed over the handle the 30 tool is withdrawn and protector is then placed in proper position.

We claim:

A golf club protector comprising a resilient tubular member adapted to be expanded when placed on the shaft of a club, frictionally engage the same and extend over the terminal portion of a member with which said shaft is associated, said tubular member being provided with an internal 40 screw thread for facilitating the positioning of said tubular member on said club, said tubular member being provided with tapering ends whereby the latter merge with the adjoining surfaces. 45

In testimony whereof we hereunto affix our signatures this 10th day of February, 1926.

CHARLES W. HAMEL.
LOUIS J. HAMEL.
